(57) **CLAIM**

The ornamental design for footwear, as shown and described.

DESCRIPTION

FIG. 1 is a top, front, lateral perspective view of footwear, showing our new design;

FIG. 2 is a top, front, medial perspective view thereof;

FIG. 3 is a front view thereof;

FIG. 4 is a lateral view thereof;

FIG. 5 is a medial view thereof; and,

FIG. 6 is a top view thereof.

The bolder dashed broken lines depict portions of the footwear that form no part of the claimed design. The lighter dashed broken lines on the footwear upper depict stitching, which forms no part of the claimed design. The dot-dashed broken lines represent boundaries of the claimed design and form no part of the claimed design.

The claimed design includes the mirror images of the embodiment depicted that is not shown.
